UNITED STATES PATENT OFFICE.

RUDOLPH A. ANSCHUETZ, OF MERIDEN, CONNECTICUT.

DESIGN FOR A HANDLE-BAR FOR CYCLES.

SPECIFICATION forming part of Design No. 27,660, dated September 21, 1897.

Application filed August 4, 1897. Serial No. 647,130. Term of patent 7 years.

To all whom it may concern:

Be it known that I, RUDOLPH A. ANSCHUETZ, of Meriden, in the county of New Haven and State of Connecticut, have invented a new Design for Handle-Bars for Cycles; and I do hereby declare the following, when taken in connection with the accompanying drawing and the letters of reference marked thereon, to be a full, clear, and exact description of the same, and which said drawing constitutes part of this specification and represents a plan view of a handle-bar embodying my design.

This invention relates to a design for handle-bars for cycles; and it consists in the configuration as hereinafter described, and shown in the accompanying illustration.

From the central portion A of the bar the ends project upward, as at B, outward, as at C, downward, as at D, and inward, as at E, forming substantially rectangular frames at the ends of the handle-bar, all as shown in the accompanying drawing.

I claim—

The design for a handle-bar as herein shown and described.

In testimony whereof I have signed this specification in the presence of two subscribing witnesses.

RUDOLPH A. ANSCHUETZ.
